INVENTOR:
DWIGHT H. BARNWELL,
By ATTORNEY.

UNITED STATES PATENT OFFICE.

DWIGHT H. BARNWELL, OF TAFT, CALIFORNIA, ASSIGNOR TO AXELSON MACHINE COMPANY, OF LOS ANGELES, CALIFORNIA, A CORPORATION OF CALIFORNIA.

PUMP.

Application filed July 25, 1925. Serial No. 46,016.

My invention relates to oil well pumps, and it has to do particularly with a novel form of plunger.

In the oil well industry it is common practice to secure a pump barrel to the lower end of a pump tubing and near the bottom of a well. A pump plunger is free to move vertically inside the barrel and a string of sucker rods is secured to the upper part of the plunger. The sucker rod string extends through the pump tubing to a point above the surface of the ground, where it is attached to one end of a walking beam of the derrick of the well. The walking beam is oscillated by appropriate mechanism and the plunger is reciprocated inside the barrel through the medium of the string of sucker rods. The pump barrel carries a standing valve cage in which a standing valve is situated, and the pump plunger carries a working valve.

It has been found that when all other conditions remain the same, a higher efficiency of the pump is usually acquired when the standing valve and the working valve are close together.

It is an object of my invention to provide a pump in which the standing and working valves are quite close together.

It is another object of my invention to provide a pump having a novel design comprising a few parts which may be readily put together and taken apart.

It is an object of this invention to bevel the upper end of the plunger sleeve for removing sand from the inner face of the barrel.

It is quite an advantage to have the standing valve cage removable from the barrel with the plunger, for the purpose of inspection and repair, and also for draining the pump tubing. If the standing valve cage is not removable with the plunger of the pump a separate fishing job is required which takes considerable time and is somewhat expensive.

It is an object of my invention to provide a pump having a device for pulling the standing valve cage with the plunger.

In a large proportion of the wells from which oil is pumped the oil contains a considerable quantity of sand which tends to settle in any cavity or recess in the pump

mechanism in which a strong current of oil is not practically continuously flowing. Any mechanism such as the interlocking device which I use for connecting the plunger to the standing valve of my pump, must necessarily be kept free from sand which, if deposited thereon, would render it inoperative.

It is a definite feature of my pump that the bayonet slots utilized in the means for connecting the pump plunger to the standing valve are constantly washed with oil exhausted from the standing valve into the pump chamber so that no sand may be deposited in these bayonet slots and build up a barrier therein so as to prevent a union between the plunger and standing valve when this may be desired.

Other objects and advantages of this invention will be made manifest hereinafter.

Referring to the two sheets of drawings in which I illustrate my invention,

Fig. 1 is a vertical cross section taken through a pump embodying the features of my invention.

Fig. 2 is a section taken on the line 2—2 of Fig. 1.

Fig. 3 is a section taken on the line 3—3 of Fig. 1.

Fig. 4 is an enlarged fragmentary section taken through the lower end of the plunger of the pump shown in Fig. 1.

Fig. 5 is a cross section taken on the line 5—5 of Fig. 4.

Fig. 6 is an enlarged partially sectioned view of a bottom bushing of my invention.

Fig. 7 is a bottom plan view of the plunger of the pump of my invention.

Fig. 8 is a view of a lift body of my invention which is secured to a standing valve cage of the pump shown in Fig. 1, this view being taken substantially as indicated by an arrow 8 of Fig. 3.

As shown in Fig. 1, 11 denotes a pump barrel and 12 denotes a pump plunger. The pump barrel 11 comprises an outer shell 13 having a lower collar 14 secured to the lower end thereof. Inside the shell 13 is a liner 15 which is accurately ground to proper size and properly secured inside the shell 13 between the lower collar 14 and an upper collar (not shown) of the barrel 11.

A standing valve cage 16 has a conical por-

tion 17 which rests in a conical seat 18 provided by the lower collar 14. A standing valve ball 19 is adapted to rest on a seat 21 for closing a passage 22 extending through the standing valve body 16.

The plunger 12 of my invention comprises a plunger sleeve 24 which threads at its lower end 25 on a central threaded portion 26 of a bottom bushing 28. The upper end of the sleeve is beveled at 27 to form a sharp edge which scrapes sand from the liner 24, preventing the sand from lodging between the liner and the sleeve. A lower end 29 of the pump plunger sleeve 24 engages an upper annular face 30 of a skirt portion 31 which extends downwardly from the central threaded portion 26 of the bottom bushing 28. Extending upwardly from the central threaded portion 26 of the bottom bushing 28 is an upper threaded projection 33 which extends inside the pump plunger sleeve 24. A working valve cage 35 placed inside the plunger sleeve 24 has a threaded lower portion 36 which is secured on the upper threaded projection 33 of the bottom bushing 28. A threaded pin 38 is formed at the upper ends of arms 39 of the cage 35, which pin 38 is threaded into a socket 41 of a sub-coupling 42. The sub-coupling 42 is secured to the lower end of a string of sucker rods 43, this string of sucker rods 43 extending upwardly through the well to the surface of the ground, attaching to a walking beam and serving to reciprocate the plunger 12 inside the barrel 11. An annular ledge 45 of a seat member 44 is clamped between an upper annular face 47 of the bottom bushing 28 and an annular shoulder 48 of the working valve cage 35. A lower cylindrical portion 50 of the seat member 44 extends into the upper end of the threaded projection 33 and engages a cylindrical face 51, whereas an upper cylindrical portion 52 of the seat member 44 extends inside the lower part of the working valve cage 35 and engages an inner cylindrical face 54 thereof. A working valve ball 55 is carried between the legs 39 of the cage 35, this ball being adapted to engage the upper end of the seat member 44 for closing a passage 56 therethrough.

As clearly shown in Fig. 4, the skirt 31 has a cylindrical bore 60 which is gradually enlarged at 61 at the lower end of the skirt 31. Extending into the bore 60 in radial directions and in diametral opposed positions are cylindrical engagers 63.

As clearly shown in Fig. 8, a threaded portion 65 of a body 66 is secured in an upper threaded portion 67 of the standing valve cage 16. Hooks 68 of the body 66 are arranged on each side of a diametral channel 78. The hooks 68 comprise rigid arms 71, from the upper ends of which there extend bridge portions 72. Extending downwardly from the ends

of the bridge portions 72 are resilient arms 73 having enlargements 74 formed at the lower end thereof. Slots 76 are provided between the rigid and resilient arms 71 and 73, below the bridges 72. The hooks 68 have semi-cylindrical outer faces 77 which are formed on a radius slightly smaller than that of the cylindrical bore 60 of the skirt 31 so that the hooks 68 may enter thereinto.

During the operation of the pump just described, the plunger 12 is reciprocated by means of the string of sucker rods 43. During the down stroke of the plunger the working valve ball 55 is removed from its seat, and oil in the lower end of the barrel 11 passes through the opening in the bottom bushing 28 to a point above the ball 55. During the up stroke of the plunger, the ball 55 is seated and oil above the working valve is elevated. During this time the oil passes from the exterior of the barrel 11 to the interior thereof below the plunger 12. The standing valve ball 19 is removed from its seat and oil passes into the barrel through the passage 22 of the standing valve cage 16. The standing valve ball 19 is closed during the down stroke of the plunger and is open during the up stroke of the plunger, whereas the working valve ball 55 is seated during the up stroke of the plunger and unseated during the down stroke of the plunger.

As previously mentioned, it is very desirable to have the working valve cage removable with the plunger. When it is desired to remove the plunger 12 and the standing valve cage 16, the plunger is lowered beyond its normal stroke so that the hooks 68 enter the cylindrical bore 60 of the skirt 31. The engagers 63 extend into the diametral channel 78 formed between the hooks 68. When the plunger has been lowered sufficiently to move the engagers 63 to the lower end of the diametral channel 78, the plunger is rotated and lifted very slowly. This moves the engagers 63 into the slots 76 of the hooks 68. In passing into the slots 76, the engagers 63 engage the enlargements 74 of the resilient arm 73, thus springing the arm 73 outwardly until these engagers pass by these enlargements 74, at which time the resilient arms return to normal position. The resilient arms and enlargements prevent an accidental disconnection between the engagers 63 and the hooks 68. When the engagers rest in the hooks 68, the standing valve cage 16 may be readily lifted with the plunger 12 to the surface of the ground.

The construction of my invention, as shown clearly in Fig. 1, permits the standing valve and the working valve to be situated close together so that the efficiency of the pump may be as high as possible. The construction of the plunger of my invention is quite simple. As is obvious from the

drawings, it requires but few parts which are of novel design and may be readily assembled and disassembled.

I claim as my invention:

- 5 1. In a deep well pump, the combination
of: a barrel; a plunger slidably disposed in
said barrel; a standing valve removably
seated adjacent the lower portion of said
barrel, said standing valve having a body
10 with a fluid passage, a valve member in said
passage, and a cap provided upon the upper
portion of said body, a fluid passage extend-
ing entirely through said cap in an axial
direction; locking means formed on said cap
15 about said axial passage; and interlocking
means formed upon said plunger and adapt-
ed to engage said locking means for lifting
said standing valve with said plunger.

2. In a deep well pump, the combination
20 of: a barrel; a plunger slidably disposed in
said barrel; a standing valve removably
seated adjacent the lower portion of said
barrel, said standing valve having a body
25 with a fluid passage, a valve member in said
passage, and a cap provided upon the upper
portion of said body, a substantially tubular
upward extension being provided centrally
upon said cap, said extension connecting
30 with said fluid passage to provide an up-
ward continuation thereof; locking means
formed upon said extension; and interlock-
ing means formed upon said plunger and
adapted to engage said locking means for
35 lifting said standing valve with said plunger.

3. In a deep well pump, the combination

of: a barrel; a plunger slidably disposed in said barrel; a standing valve removably seated adjacent the lower portion of said barrel, said standing valve having a body with a fluid passage, a valve member in said passage, and a cap provided upon the upper portion of said body, a substantially tubular upward extension being provided centrally upon said cap, said extension connecting with said fluid passage to provide an upward continuation thereon, there being a bayonet slot formed in said tubular extension; and a locking pin provided upon said plunger and adapted to be positioned in said bayonet slot to permit the lifting of said standing valve by said plunger. 40 45 50

4. In a deep well pump, the combination of: a barrel; a plunger slidably disposed in said barrel; a standing valve removably seated adjacent the lower portion of said barrel; locking means formed upon said standing valve; and interlocking means formed upon said plunger and adapted to engage said locking means for lifting said standing valve with said plunger, there being a fluid discharge opening in said standing valve which directs fluid discharged therefrom in a manner to wash said locking means and substantially prevent accumulation of solids therein. 55 60 65

In testimony whereof, I have hereunto set my hand at Taft, California, this 14th day of July, 1925.

DWIGHT H. BARNWELL.
